UNITED STATES PATENT OFFICE.

GUSTAF LIBERT REENSTIerna, OF BOSTON, MASSACHUSETTS, ASSIGNOR
TO WILLIAM F. BEAL, OF SAME PLACE.

SLIDING-DOOR FASTENER.

SPECIFICATION forming part of Letters Patent No. 622,167, dated March 28, 1899.

Application filed April 26, 1898. Serial No. 678,842. (No model.)

To all whom it may concern:

Be it known that I, GUSTAF LIBERT REENSTIerna, a citizen of the United States, residing at Boston, in the county of Suffolk and 5 State of Massachusetts, have invented new and useful Improvements in Fastening Devices for Sliding Doors, of which the following is a specification.

This invention relates to improvements in 10 fastening devices for sliding doors; and it has for its object to facilitate the opening and closing of the door, and when used on steam or street cars or on board vessels it serves to prevent rattling and the accidental opening 15 of the door, as will hereinafter be more fully shown and described, reference being had to the accompanying drawings, wherein—

Figure 1 represents a front elevation of a 20 sliding door provided with my improved fastening device. Fig. 2 represents a rear elevation of the same. Fig. 3 represents an enlarged horizontal section on the line 3 3, shown in Fig 1; and Fig. 4 represents an enlarged vertical section on the line 4 4, also shown in 25 Fig. 1.

Similar letters refer to similar parts wherever they occur on the different parts of the drawings.

A represents a sliding door, and B represents the hollow door-casing into which the door is moved when it is being opened, as is 30 common in sliding-door devices.

C represents the opposite door-casing, which serves as a stop against the door when closed.

To one side of the door is preferably secured a metal plate D, provided with ears or 35 projections d d, in which is journaled a vertical bar E, to which the handle E' is attached or made integral with it, as shown. On the 40 interior of the plate D is pivoted at f the latch F, the free end of which is hooked, as shown at f', and adapted to interlock with a plate or projection C', secured to the casing C, as shown in Fig. 3.

G is a spring interposed between the latch F and the door A, as shown in Fig. 3, and it serves to hold the hooked end interlocked with the projection C' when the door is closed. When the door is open, the latch is held by 45 the influence of said spring against the inside of the plate D. In one piece with the handle-bar E is made a bent lever or cam projection

e, the free end of which passes through a perforation D' in the plate D and lies in contact with the latch F, as shown in Figs. 2 and 3. 55

To open the door from the side where the handle E' is located, it is only necessary to take hold of such handle and pull it in the direction of arrow shown thereon in Fig. 3, causing the lever e to depress the latch F 60 against the spring G sufficiently to disengage said latch from the projection C', thus allowing the door to be freely opened. To close the door, the operator takes hold of the handle E' and moves it in an opposite direction 65 to that shown by the arrow, causing the rocker-bar E to be brought in contact with the door-plate D, thus preventing the handle from turning during the closing operation of the door. As the door reaches its closed position 70 the yielding latch F is caused to be interlocked with the projection C', as shown in Fig. 3. On the opposite side of the door is pivoted to brackets h h a vertical bar H, to which is attached the handle H'. Preferably 75 integral with the rocking bar H is made a lever or projection h', to which is pivoted a link I, the inner end of which is pivoted to the latch F, as shown in Fig. 3. If it is desired to open the sliding door from the side 80 on which the handle H' is located, it is only necessary to take hold of said handle and move it in the direction of the arrow shown thereon in Fig. 3, causing said handle to be rocked sufficiently to cause the latch F to be 85 disconnected from the projection C' and allowing the door to be opened by further pressure on said handle H' in the direction of the arrow shown in Fig. 3.

In closing the door the operator takes hold 90 of the handle H' and moves it in a direction opposite to that shown by the arrow in Fig. 3, and during such closing motion the bar H or its lever h' serves as a stop to prevent the handle H' from being rocked. As the door 95 reaches its closed position it is caused to be locked by the yielding hooked latch F and projection C' the same as if actuated from the opposite side.

It will thus be seen that the door can be 100 closed and opened from either side and locked in closed position simply by manipulating a pivoted handle arranged on opposite sides of the sliding door without the need of inde-

pendent locking devices, making the invention particularly well adapted for sliding doors on street or railway cars, &c., where the vehicle is exposed to jars tending to open the door when not provided with a locking device.

Having thus fully described the nature, construction, and operation of my invention, I wish to secure by Letters Patent and claim—

1. The combination with a sliding door, its casing, and a locking projection on said casing, of a pivotally-mounted spring-pressed latch on said door adapted to engage said projection, a pair of pivotally-mounted handles, laterally-extending arms or levers on said handles, one of which is adapted to engage said latch, and a link connecting the arm on the other of said levers with said latch, substantially as described.
- 15 2. The combination with a sliding door, its

casing, and a locking projection on said casing, of a horizontally-movable, spring-pressed latch, pivotally mounted in a socket in said door, pivotally-mounted handles on opposite sides of the door, each adapted to swing in a horizontal plane and each provided with a laterally-extending arm or lever, one of said arms or levers projecting through a slot in the door and engaging said latch and the other connected to said latch by a link which extends through an opening in the door, substantially as described.

In testimony whereof I have hereunto set my hand in presence of two subscribing witnesses.

GUSTAF LIBERT REENSTIerna.
